UNITED STATES PATENT OFFICE.

BENJAMIN WOLHAUPTER, OF NEW YORK, N. Y., ASSIGNOR TO THE RAIL JOINT COMPANY, OF NEW YORK, N. Y., A CORPORATION OF NEW YORK.

INSULATED RAIL-JOINT.

No. 920,801.

Specification of Letters Patent.

Patented May 4, 1909.

Application filed April 24, 1907. Serial No. 370,107.

To all whom it may concern:

Be it known that I, BENJAMIN WOLHAUPTER, a citizen of the United States, residing at New York city, in the county of New York and State of New York, have invented certain new and useful Improvements in Insulated Rail-Joints, of which the following is a specification.

This invention relates to insulated rail joints of the type embodying a two part or sectional supporting base for the rail ends, whereby a separate supporting base section is provided for each rail end, admitting of such a disposition of the insulation that there is no insulating material which is required to carry the load or weight of the passing trains.

To this end the invention primarily contemplates an improvement in the construction of the joint bars whereby the latter shall be more effectively reinforced at the weak point of the joint, that is, at a point between the ties upon which the joint is supported.

25 A further object in this connection is to generally improve the reinforcing and stiffening of the joint bars throughout their entire length, while at the same time preserving the feature of providing each joint bar 30 along one end portion with a short length base section affording one rail end the support of the ties on both sides of the meeting point of the rails without contact with the corresponding base section.

35 With these and many other objects in view, which will more readily appear as the nature of the invention is better understood, the same consists in the novel construction, combination, and arrangement of parts, 40 hereinafter more fully described, illustrated, and claimed.

The essential feature of the invention above indicated is susceptible to embodiment in a variety of forms of joints, particularly of the types disclosed in my companion applications, to-wit:—filed November 8, 1906, Serial No. 342,523 (now Patent No. 868,517, Oct. 15, 1907); filed November 8, 1906, Serial No. 342,524 (now Patent No. 868,518, Oct. 15, 1907); filed December 6, 1906, Serial No. 346,643 (now Patent No. 868,520, Oct. 15, 1907), and filed January 26, 1907, Serial No. 354,284 (now Patent No. 868,384, Oct. 15, 1907), but a few of the preferred embodiments of the invention are

shown in the accompanying drawings, in which—

Figure 1 is a sectional perspective view of an insulated rail joint of the general Weber type embodying the joint bar reinforcement contemplated by the present invention. Fig. 2 is a vertical sectional view of the joint shown in Fig. 1, the plane of section being indicated by the line 2—2 in Fig. 1. Fig. 3 is a top or base plan view showing the opposite joint sections or shoes in their matching relation; said view omitting the insulation and bolts, and indicating by dotted lines the separate rail ends. Fig. 4 is a sectional perspective view of another form of joint embodying the reinforcement contemplated by the present invention. Fig. 5 is a similar view of another form of joint embodying the reinforcement claimed herein. Fig. 6 is a side elevation and projected end view of a rolled joint section or shoe illustrating a practical means of providing the centrally depending reinforcing girder at the bottom edge of the side joint bar at a point which comes between the ties.

Like references designate corresponding parts in the several figures of the drawings.

As indicated, the present invention is specially applicable to those types of insulated rail joints embodying a two part or sectional supporting base for the rail ends, and wherein each side joint bar is provided along one end portion with a short length base section affording a support for one rail end. Hence, the various forms of insulated rail joints involving said base construction may be provided with the special reinforcement claimed herein. This reinforcement may likewise be associated with side joint bars of various designs, irrespective of whether these joint bars constitute the upright members of joint shoes or shoe angles, or are in the form of angles or splice bars arranged over the rail bases, and disposed beneath the rail heads.

Referring to the specific exemplifications of the invention shown in the drawings, Figs. 1, 2, and 3 of the latter illustrate an insulated joint comprising in its organization the service rails 1 and 2, the opposite side joint bars 3 and 4, the wooden filler blocks 5 interposed between the side joint bars and the sides of the rails, and the usual series of joint bolts 6. In this joint, the side joint bars 3 and 4 are shown as constituting the upright mem-

bers of shoe angles, and each of the same is provided along one end portion thereof with a short length base section 6 affording one rail end the support of the ties on both sides 5 of the meeting point of the rails 1 and 2 without contact with the corresponding base section of the other joint bar. In this particular, the joint bars 3 and 4 are of the same design and subserve the same functions as the 10 corresponding members disclosed in my companion applications aforesaid, but a distinguishing feature in the design and construction of the side joint bars in the present invention resides in providing each side joint 15 bar along its bottom edge with an integral offstanding foot 7 constituting a reinforcing and spiking flange, and also with a centrally arranged depending reinforcing girder 8. The reinforcing girder 8 which depends from 20 the bottom edge of each side joint bar occupies a position intermediate the ends of the bar, and hence at the middle of the joint in the transverse plane of the meeting ends of the rails, thereby disposing the said girder at 25 a point between the two ties upon which the joint is supported. This disposition of the depending reinforcing girder 8, in conjunction with the offstanding foot or reinforcing flange 7, provides a material stiffening and 30 strengthening of the joint bar not only through its entire extent, but also at a point where most needed, viz: at the middle of the joint.

The centrally arranged depending girder 8 35 of each joint bar may be formed in various ways on the bar, in the process of manufacturing the latter, and in the construction suggested in Figs. 1, 2, and 3, it will be observed that the said girder 8 may be rolled as 40 a part of the foot or flange 7 and severed from the latter along the lines of cut designated by the reference number 9 in Fig. 1 of the drawings, thereby permitting the sections of the foot or flange 7 to be bent to the 45 relative positions shown in the drawings.

In the joint shown in Figs. 1, 2, and 3 of the drawings, any suitable insulating expedients may be utilized to complete the insulation thereof, such for instance as the insulating end post 10 between the rail ends, the insulating strips 11 between each base section 6 and the opposite joint bar, and the insulating sleeves or bushings 12 arranged in the bolt holes in the rail webs and receiving the joint bolts therethrough. These insulating features, however, may be varied without in any way affecting the present invention.

Another modification of the invention is 60 shown in Fig. 4 of the drawings illustrating an insulated joint comprising the service rails 1 and 2, the opposite side joint bars 13 and 14, the filler blocks 15 interposed between said joint bars and the sides of the rails, and 65 the joint bolts 16. This joint also includes

in its construction the feature of providing each side joint bar along one end portion thereof with a base section 17 affording a support for one rail end and maintaining the same relation to the base section of the opposite side joint bar as illustrated in Fig. 3 of the drawings. Also, the joint shown in Fig. 4 includes the details of suitable insulation 18 between the rail ends, and insulation 19 between each base section and the opposing side joint bar, and it will be further observed that, in the design of joint described, the side joint bars 13 and 14 are illustrated as being set at an angle to a vertical plane and binding against correspondingly inclined bearing faces 20 on the outer sides of the wooden filler blocks 15. In connection with this construction of joint, the present invention contemplates the practical feature of providing each side joint bar at its bottom edge 80 with an offstanding reinforcing and spiking foot flange 21 and having the central or intermediate portion of this flange bent downwardly, as at 22, to provide an intermediate depending reinforcing girder occupying a position between the ties in the transverse plane of the joint between the meeting ends of the rails, thus effecting a strong reinforcing of the joint bars at the middle of the joint. In connection with the construction described, it will be further observed that the form of the foot flange 21 provides outstanding reinforcing webs or ribs 23 at the end edges of the girder 22 forming direct integral continuations of the main portions 100 of the foot flange 21. This same design of reinforcement, such as shown in Fig. 4, is illustrated in Fig. 5 as applied to an angle bar type of insulated rail joint. Referring to the latter, the same includes the service rails 1 and 2, the side joint bars 24 and 25, and the series of joint bolts 26. Also, in this design of joint, each of the side joint bars is provided along one end portion thereof with an integral short length base section 27 affording 110 a support for one rail end and occupying the same relation to the base section of the opposite side joint bar as shown in Fig. 3 of the drawings. Furthermore, the special design of joint shown in Fig. 5 includes the details of 115 suitable insulation 28 between the meeting ends of the rails, side insulating sheets 29 between the side joint bars and the rail sides, and suitable insulation 30 for the joint bolts.

A distinctive characteristic of the joint 120 shown in Fig. 5 resides in the fact that the side joint bars 24 and 25 are in the form of continuous angle bars fitting over the rail bases and into the sides of the rails beneath the heads thereof. Each of said side joint 125 bars 24 and 25 (of the angle bar type) is provided at its bottom edge with the offstanding reinforcing and spiking foot flange 31 having bent downwardly therefrom the centrally located depending reinforcing girder 32 and the 130

outstanding reinforcing webs or ribs 33, said members 31, 32, and 33 being of the same design and arrangement and subserving the same functions as the corresponding members 5 21, 22, and 23 shown in Fig. 4 of the drawings.

Other designs of insulated rail joints embodying the two part base construction may obviously be provided with a centrally located girder reinforcement for the side joint bars of the character described, and while various expedients may be resorted to in forming this reinforcement, a practical method of construction is suggested in Fig. 6 of the drawings. This figure of the drawings illustrates a rolled joint section essentially consisting of an upright side joint bar 34 provided with an integral base section 35, and also provided at its lower edge with an integral 10 offstanding continuous foot flange 36. In addition to these elements, the side joint bar 34 is illustrated as provided at an intermediate point, or centrally between its ends, with a depending reinforcing girder 37 corresponding in position and function to the girders 8, 22, and 23 herein referred to, but in the formation of the rolled section shown in Fig. 6, it will be observed that the foot flange 20 36 is rolled as a continuous element, and the section also has rolled thereon a continuous

depending bottom flange, the end portions of which latter are sheared off to leave the centrally arranged depending girder 37. In this connection it will be observed that the sheared-off end portions 38 of the rolled flange, from which the girder 37 is formed, are indicated by the dotted lines and shaded portions in the side elevation of Fig. 6.

Other means of forming the girder reinforcement may be resorted to without departing from the invention.

I claim:

A two-part-base rail-joint comprising, in combination with the rails, opposite side joint bars each of which is provided along 45 one end portion thereof with an integral base section for supporting one of the rail ends, and at a central point with an integral depending reinforcing girder extending partly 50 along that portion of the bar having a base section and partly along that portion of the bar having no base section, and insulating means.

In testimony whereof I hereunto affix my 55 signature in the presence of two witnesses.

BENJAMIN WOLHAUPTER.
